UNITED STATES PATENT OFFICE.

LEONARD G. VAN NOSTRAND, OF SCRANTON, PENNSYLVANIA.

GRATE-BAR.

1,122,388.

Specification of Letters Patent. Patented Dec. 29, 1914.

Application filed August 1, 1913. Serial No. 732,402.

To all whom it may concern:

Be it known that I, LEONARD G. VAN NOSTRAND, a citizen of the United States of America, and resident of Scranton, in the county of Lackawanna and State of Pennsylvania, have invented certain new and useful Improvements in Grate-Bars, of which the following is a specification.

This invention relates to stoves and furnaces and particularly to grates and grate bars, the said invention relating especially to means in a leaf for a shaking grate or the leaf of a dumping grate or to stationary bars with which a movable leaf coats to form a grate.

An object of the present invention is to provide a leaf for a grate having novel means for distributing air to the under surface of a fire bed for the purpose of insuring practically uniform combustion throughout the fire bed and it is designed as an advantageous construction as compared with such devices as those which have air holes connected together, or those devices having corrugated surfaces for the reason that air cannot travel from one hole or portion of the fire bed to another but each aperture and the ducts connected therewith extend over the whole area and advantageously affect the hitherto dark places of a fire bed, the invention operating to spread the supply of air effectually.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a plan view of the grate embodying the invention; and Fig. 2 illustrates a side elevation thereof, the same being partly in section, on the line 2—2 of Fig. 1.

In these drawings 3 denotes the supporting bar for the grate bar, the same having stationary and integral portions 4 provided with a series of ribs 5. As shown in the drawing, each leaf 6 has a series of apertures

7 therein, which apertures are so positioned as to provide passages for air 55 through the leaf and the upper surface of each leaf has a series of elongated recesses 8 radiating from an aperture 7, the recesses of some of the apertures extending beyond 60 and being nested, as it were, with relation to the elongated recesses of certain other apertures. Furthermore, the portions 4 have elongated recesses 9 which form continuations of the recesses 8, thus effecting 65 an extension of the duct or conduit for air formed by certain of said recesses. It will be observed that as air enters the aperture and radiates through the ducts formed by the recesses, air may be admitted under 70 any one of the sections 4, thus effectually distributing air under practically the whole area of the said fire bed, as stated.

By reason of the fact that none of the ducts from any one aperture merge with any 75 one of the ducts radiating from any other aperture, it follows that air cannot pass transversely or longitudinally of the grate from one duct to another but that each aperture and its ducts constitute a separate air 80 supply medium which insures proper distribution of the air and prevents the formation of what are usually termed "dark spots" in the fire bed, this owing to the fact that sufficient air is caused to reach all portions 85 of the fire bed to support combustion.

It is not necessary that the ducts be uniform in length or that they be symmetrical with relation to the apertures and I have therefore shown some of the ducts longer 90 than others for the purpose of distributing the air to effect the most advantageous result.

I claim

1. A grate bar comprising a metal plate 95 having a plurality of cone shaped openings extending therethrough, and having independent non-communicating grooves, said grooves radiating from the edges of the respective openings, the terminals of the respective grooves being in close proximity with each other for forming air channels over the surface of the plate.

2. A grate bar comprising a plate having openings extending therethrough, and having 100 non-communicating grooves radiating from

the openings, said grooves forming air channels over the surface of the plate.

3. A grate bar comprising a plate having openings there through, and having non-communicating grooves radiating from the openings, the grooves being arranged in the plate whereby the terminals thereof are positioned between the adjacent grooves of the

adjacent openings to form air channels over the surface of the plate.

In testimony whereof, I affix my signature in the presence of two witnesses.

LEONARD G. VAN NOSTRAND.
